TOILET TRAINER

Simeon L. Halenar, 11409 S. King Drive,
Chicago, Ill. 60628

Filed June 7, 1972, Ser. No. 260,708

Term of patent 14 years

Int. Cl. D19—07

U.S. Cl. D25—1

FIG. 1

FIG. 2

FIG. 3

FIG. 1 is a perspective view of a toilet trainer embodying my new design;

FIG. 2 is a side elevational view thereof; and

FIG. 3 is an elevational view taken from a plane parallel to that indicated by line III—III in FIG. 2.

I claim:

The ornamental design for a toilet trainer, as shown.
